UNITED STATES PATENT OFFICE.

HENRY I. WILLIS, OF COLFAX, WASHINGTON.

AUTO CHAIN FASTENER.

Application filed August 28, 1926. Serial No. 132,173.

This invention relates to connecting links, and more particularly connecting links designed for use in connection with anti-skid chains for motor vehicles.

5 The primary object of the invention is to provide a connecting link which may be readily and easily locked in position on a chain, the construction being such that all danger of the link becoming accidentally disconnected will be eliminated.

10 A still further object of the invention is the provision of a connecting link wherein the locking element thereof may be operated by the hands of the person applying or removing the chain, without the use of tools.

15 With the foregoing and other objects in view which will appear as the description proceeds, the invention resides in the combination and arrangement of parts and in the 20 details of construction hereinafter described and claimed, it being understood that changes in the precise embodiment of the invention herein disclosed, may be made within the scope of what is claimed, without 25 departing from the spirit of the invention.

Referring to the drawing:

Figure 1 is a plan view of a connecting link constructed in accordance with the invention, the locking lever thereof being 30 shown in dotted lines, in its inactive position.

Figure 2 is a side elevational view of the locking link.

35 Figure 3 is a side elevational view thereof showing the pivoted arm in dotted lines, as moved to its inactive position.

Figure 4 is a sectional view taken on line 4-4 of Figure 3.

40 Figure 5 is a sectional view taken on line 5-5 of Figure 3.

Referring to the drawing in detail, the device includes a body portion indicated by the reference character 5 which is formed of a length of heavy metal having one end 45 thereof bent inwardly on itself as at 6 to provide an eye for the reception of a link of a chain such as indicated at 7.

50 The opposite end of the body portion 5 is bifurcated, the furcations being bent inwardly upon the body of the link to provide eyes 8, the eyes being designed to receive the pivot pin 9 that connects the locking arm 10 to the body portion. This locking arm is substantially long and extends to a point 55 adjacent to the eye 6 as clearly shown by Figure 2 of the drawing, where the same is

provided with a notch or keeper for the reception of the locking ring 11, which is loosely mounted on the contracted portion 12 of the body portion 5.

60 A notch indicated at 13 is provided in the locking arm 10, at a point adjacent to the pivot pin 9 which notched portion provides a keeper for the link 14 at the opposite end of the chain.

65 Pivotedly supported on the body portion 5 is a locking lever 15 which has a right angled end portion 16 wedge-shaped as shown by Figure 2 so that the right angled end 16 may be forced under the arm 10 to move the same 70 upwardly into close engagement with the ring 11.

75 An offset portion indicated at 17 is formed on the body portion and has an opening formed therein to receive the downwardly extended finger 18 of the locking lever 15 which is adapted to spring into the opening as the finger 18 moves across the body portion in its movement to its active position.

80 In order that the locking lever may be conveniently operated, an upwardly extended finger 19 is provided, which may be grasped by the fingers of the operator and lifted to move the pin 18 out of the opening so that the locking lever may be moved laterally to 85 its inactive position.

90 It is thought that in view of the foregoing detailed description, a further detail description of the operation of the device is unnecessary.

I claim:

1. A locking link for chains including a body portion, means for securing a link of a chain to one end of a body portion, a locking arm pivotally supported by the body portion, and said arm adapted to be swung over a link of a chain, said arm having a cut out portion in its upper surface, a ring member carried by the body portion and adapted to be slid over the body portion, and means for forcing the arm upwardly into engagement with the ring member to lock the arm against movement.

105 2. A locking link for chains including a body portion, means for securing a link of a chain to one end of a body portion, a locking arm adapted to be swung over a link of a chain to removably secure the last mentioned link to the body portion, a locking ring adapted to be slid over the arm, and a locking lever carried by the body portion and adapted to be moved under the arm to 110

force the arm into engagement with the locking ring.

3. A locking link for chains including a body portion, means for securing an end link of a chain to one end of a body portion, a locking arm carried by the body portion and adapted to be swung over an end link of a chain to lock the second mentioned link to the body portion, a locking ring adapted to be slid over the arm, and a locking lever having a wedge-shaped end adapted to be forced under the arm to move the arm into close engagement with the locking ring.

4. A locking link for chains including a body portion, a locking arm pivotally con-

nected to the body portion at one end thereof, said arm adapted to swing over the body portion to lock a chain link to the body portion, a ring slidable on the body portion and engaging the arm to hold the arm against movement, a locking lever having a right angled extremity, pivotally connected to the body portion, the right angled extremity adapted to be forced under the lever to move the lever upwardly into engagement with the ring, and means for locking the locking lever against accidental displacement.

In testimony that I claim the foregoing as my own, I have hereto affixed my signature.

HENRY I. WILLIS.
